UNITED STATES PATENT OFFICE.

GEORGE R. CLARK, OF WASHINGTON, DISTRICT OF COLUMBIA.

WRITING-PAD.

1,361,366.

Specification of Letters Patent.

Patented Dec. 7, 1920.

Application filed September 10, 1918. Serial No. 253,427.

To all whom it may concern:

Be it known that I, GEORGE R. CLARK, a citizen of the United States, and a resident of Washington, in the District of Columbia, have invented certain new and useful Improvements in Writing-Pads, of which the following is a specification.

My invention relates to improvements in writing pads, and it consists in the constructions, combinations, and arrangements herein described and claimed.

An object of my invention is to provide a writing pad which includes as one of the most important features, an endless sheet of paper arranged to be advanced step by step, and capable of being reversed so that both sides of the paper may be filled with writing before it is discarded.

Another object of the invention is to provide a writing pad having an endless sheet of paper arranged to be advanced the width of a writing line by the actuation of a finger piece, the arrangement being such that when one side of the paper is filled, the other side may also be written on by simply reversing the pad, the finger piece being actuated as before.

Other objects and advantages will appear in the following specification, reference being had to the accompanying drawings in which:—

Figure 1 is a perspective view of the improved writing pad,

Fig. 2 is a side elevation, parts being shown in section,

Fig. 3 is a longitudinal section of the writing pad illustrating the disposition of the endless paper sheet,

Fig. 4 is a horizontal section showing the arrangement of the mechanism on the inside,

Fig. 5, is a longitudinal section similar to Fig. 3, the paper sheet being omitted,

Fig. 6 is a cross section on the line 6—6 of Fig. 2,

Fig. 7 is a detail horizontal section, illustrating more clearly the operation of the pawl and ratchet mechanism at one end by means of the pitman and bell crank,

Fig. 8 is a detail section illustrating the parts in Fig. 7 more clearly,

Fig. 9 is a detail view of the cam and rack-bar devices which operate in conjunction with the pawl and ratchet at each end,

Fig. 10 is a detail cross section illustrating the arrangement of the pawl and ratchet devices at one end of one of the feed rolls,

Fig. 11 is a diagrammatic view illustrating the manner of winding the paper,

Fig. 12 is a detail perspective view of the variable stop 43, and

Fig. 13 is a detail perspective view of the ratchet disk and pawl.

In its general aspect, the improved writing pad consists of a frame 1. The frame comprises the side members which have inwardly bent flanges 2 at the extremities. These flanges extend to a place slightly beyond the upper and lower belt rolls 3 and 4, where they merge with plates 5 and 6.

These plates extend entirely across beneath the paper 7, thus connecting the side members 1 of the frame and forming a support for the paper when the pad is used in writing. Endless belts 8 and 9 are applied to the upper and lower pairs of belt rolls 3 and 4, respectively. The outer strands of these belts run over the plates 5 and 6 as can be clearly observed in Figs. 3 and 5.

In applying the paper, which is supplied in a long sheet or in any event, a sheet long enough to serve the intended purpose in the writing pad, one end is fastened to the upper belt 8 by means of a hook 10 or any other suitable fastening device that may be devised for the purpose. This is shown in diagrammatic Fig. 11.

The paper is then initially wound on the upper belt 8 as shown in Fig. 3, by applying the key 11 to the square protruding end 12 of the shaft of the upper belt roll 3 at the left in Figs. 3 and 11. After the paper sheet is nearly all wound up, the free end is applied to the feed roll 13 at the right, guided over the lower belt 9, over the idler 14 at the left, and fastened to the belt 9 by a hook 15 or other suitable fastening device.

In actual practice, there is space enough between the paper body 7 at the left in Fig. 11 and the adjacent feed roll 16, to enable the introduction of the fingers in securing the fastener 15 to the belt 9 in the manner just explained. This space is more clearly shown in Fig. 1, where it will be observed there is room enough for the introduction of the fingers.

The paper after being secured on the lower belt 9, will in the subsequent operation of the device, wind itself around the belt as partly indicated in Fig. 11, until the paper body is finally transferred from the upper belt 8 to the lower one. On this occa-

sion the paper sheet should be completely filled with writing on one side. Then by simply turning the writing pad over endwise and changing the attachment of the 5 then free end of the paper, the reverse and clean side of the paper will be exposed so that it too can be filled with writing.

In changing the attachment of the free end of the paper as just stated, the hook 10 is released, the end of the paper is 10 removed from around the idler 14, is applied to the feed roll 16 at the left similarly as it was formerly applied to the feed roll 13 at the right, is stretched over the 15 upper belt 8, applied to the idler 17 at the right, whereupon the hook 10 is fastened to the belt 8 in the space accessible beneath the feed roll 13. By a moment's consideration 20 it will be readily understood that the writing exposed at *w* in Fig. 11, will be covered when the paper is turned around and fastened on the other side, and on operating the feed rolls in the same direction, the paper is pulled off of the belt 9, just as it 25 was pulled off of the belt 8 by the feed roll 13 in the first instance.

Before describing the operation of advancing the paper step by step in writing, it should first be explained that presser rolls 30 18 and 19 bear against the feed rolls 13 and 16, respectively in order to hold the paper in contact with the particular feed roll to which the paper happens to be applied.

Each presser roll is journaled to rotate 35 freely in bearings of yokes 20 and 21. These yokes are concealed on the inside of the frame, on the side members of which they are supported by suitable bearings 22 as shown in Fig. 8. The bridge portions of 40 the yokes are pressed together by springs 23 as shown in Fig. 4. These springs exert tension on the presser rolls so that the presser rolls keep in firm contact with the respective feed rolls.

45 In order to throw the pressure rolls out for the insertion of the ends of the paper sheet, cams 24 on a transverse shaft 25 are disposed at the lateral extremities of the yokes in the space between the bridge portions. 50 Upon turning the knurled head 26 at one end of the shaft 25, through a quarter turn, the cams are made to separate the yokes for the purpose described.

A finger piece 27 on a pitman 28, is exposed at one side of the frame as shown in 55 Fig. 1. The finger piece is depressed upon the writing of each line, so that the paper is moved upwardly one space. Thus in writing, the writing pad is held in the left hand 60 while the wrist of the right hand is supported near the bottom of the pad. One of the fingers of the left hand is used to actuate the finger piece 27 to move the paper up, it therefore becoming unnecessary to

move the right hand down as the lines are 65 written.

The pitman 28 extends across the frame in the inside wherein it reciprocates in a bearing 29. A pin 30 near the inner extremity of the pitman, operates in the 70 forked end of a bell crank 31. The other forked end of the bell crank receives the pendent pin 32 of a longitudinally extending rack bar 33.

The rack bar 33 has short racks 34 at each 75 end. Each rack 34 meshes with a pinion 35 which is integral with a disk 36. The disk itself is loose on the exposed end of the feed roll shaft. The disk 36 has a peripheral notch 37 through which the pin 38 of a pawl 39 on the other side, extends. The pawl is pivoted on the disk 36 at 39^a in Figs. 8 and 13.

The pawl 39 is normally held out of engagement with the ratchet 40 secured on 85 the adjacent end of the feed roll which is operated thereby, by means of a cam 41 which is stationarily supported by the arm 41^a. As will be observed in Fig. 9, the arrangement is such that the pin 38 rides back 90 over the stationary cam 41 on each return stroke of the finger piece 27 so that the pawl 39 is again lifted out of engagement with the ratchet disk 40. A spring 42 presses the pawl into engagement with the ratchet, 95 when the pin 38 rides over the end of the stationary cam 41 in making a stroke.

In order to adjust the stroke of the rack bar 33 and consequently to vary the space between the lines of writing, the inward 100 thrust of the pitman 28 can be regulated in length by means of the regulator 43, shown in Fig. 7. The regulator consists of a slide- 105 able piece with a plurality of steps. A knurled head 44 on the outside enables the movement of the regulator so that any one of the steps can be brought into alinement with the end of the pitman 28.

It will readily be observed that the thrust 110 of the pitman is limited to the distance between the end of the pitman and the adjacent surface of the particular one of the steps, so that the distance of movement of the pawl 39 is regulated accordingly. Thus the feed roll is made to move a greater or 115 less distance.

A spring 45 shown in Fig. 6, returns the pitman 28 and finger piece 27 to the normal position after each depression. Intermeshing gears 46, 47 on one end of each of the 120 belt rolls 3 and 4, positively drive the respective pairs of belt rolls in opposite directions as illustrated in Fig. 11. The stub axles of the feed rolls are journaled in bearings 48 at each open end of the frame as 125 shown in Fig. 8.

In order to secure a rapid back and forth motion of the paper sheet should an occa-

- sion arise where it becomes necessary to move the paper back a distance, the axle of the feed roll 13 is extended at one end and squared as shown in Fig. 4, so that the key 11 may be applied thereto as shown in Fig. 1, for the purpose described. Similarly the axle of the feed roll 16 is extended and squared, so that the key 11 may be applied to either axle.
- 10 It will readily be observed that the paper can be moved either forwardly as when used in writing, or if it be desired to move the paper back one or two spaces for the purpose of making a correction, this can be 15 done by turning either one of the feed rolls. These are free to revolve in either direction.
- 20 Casings are formed on the upper edges of the side members of the frame, to cover the gears 46 and 47 at one side. These casings are duplicated at the other side, and together these casings form legs upon which the device rests when set upon a table. The 25 legs thus support the device clear of the table and the action of the paper is therefore not interfered with. Since the operation of the device has been fully explained in connection with the description of the parts, it is thought unnecessary to repeat it.
- 30 While the construction and arrangement of the writing pad is that of a generally preferred form, obviously modifications and changes may be made without departing from the spirit of the invention or the scope 35 of the claims.

I claim:

1. A reversible writing pad, comprising a frame, paying-off paper holding means, to which one end of a paper sheet is connected 40 and then applied to a portion of the frame; receiving means to which the other end of the paper is connected, and means for producing a step-by-step motion of predetermined extent of said paying-off means, to so wind 45 the paper on the receiving means with the writing concealed, to enable writing on the clear side by turning the writing pad endwise and changing the paper connections.
  2. A writing pad, comprising a frame including plates, a pair of endless belts having strands running over the plates, a feed roll for moving a paper sheet wound on one belt and attached to the other belt having the paper sheet applied thereto, and means 55 for actuating the feed roll by intermittent strokes to unwind the paper from the one belt onto the other.
  3. A writing pad, comprising a frame including plates, a pair of endless belts having 60 strands running over the plates, a feed roll, means for actuating the feed roll by intermittent strokes to unwind a paper sheet from one belt onto the other belt said sheet being suitably connected to each belt, and means
- coöperating with said feed roll actuated 65 means varying the lengths of the strokes.
4. A writing pad, comprising a frame including plates, pairs of belt rolls journaled in the frame, a pair of endless belts carried by certain pairs of the rolls and having 70 strands running over the plates, friction means including a feed roll for unwinding a paper sheet from one belt, means for actuating the feed roll by intermittent strokes, and mutual driving means carried by the 75 belt rolls, for winding said paper sheet on the second belt as it is unwound from the first belt, said sheet being suitably connected at each end to each belt.
5. A writing pad, comprising a frame including plates, pairs of belt rolls journaled in the frame, a pair of endless belts carried by certain pairs of the rolls and having 80 strands running over the plates, friction means including a feed roll for unwinding a paper sheet from one belt to which one 85 end is attached, means for actuating the feed roll by intermittent strokes, mutual driving means carried by the belt rolls, for winding the paper on the second belt to which the 90 other end is attached as it is unwound from the first belt, and a feed roll becoming operative to advance the paper, when the filled sheet is wound on the second belt and the 95 attachment of the then free end is changed to expose the clean reverse side of the paper.
6. A writing pad, comprising a frame of side members with transverse upper and lower connecting plates enabling the writing on both sides of a paper sheet by reversing the pad and changing the accessible 100 paper connection, pairs of rollers mounted transversely of the frame adjacent to the ends of said plates, a pair of endless belts applied to pairs of the rollers and having 105 strands running on the outsides of the plates, gear connections between the rollers, feed rolls at the ends of the pad, attaching means for securing a paper sheet to both belts at the respective ends, the sheet being initially 110 wound on one belt releasable pressing means for keeping the paper in contact with the feed rolls, and means for actuating the feed rolls intermittently to secure a step by step advancement of predetermined extent of the 115 paper as the lines are written.
7. In a writing pad, a feed roll having a ratchet fixed on one end, a freely revoluble pinion and disk, the disk having a peripheral notch; a pawl for engaging the ratchet, 120 pivoted on the disk and having a pin extending through the notch, resilient means for pressing the pawl against the ratchet, means including a stationary cam normally engaging the pin and holding the pawl out 125 of contact with the ratchet, a rack bar arranged to rotate the pinion whereupon the pin rides off the cam into engagement with

the ratchet, and finger actuated means including a pitman for operating the rack bar.

8. In a writing pad, a feed roll having a ratchet fixed on one end, a freely revoluble pinion and disk, the disk having a peripheral notch; a pawl for engaging the ratchet, pivoted on the disk and having a pin extending through the notch, resilient means for pressing the pawl against the ratchet, means including a stationary cam normally engaging the pin and holding the pawl out of contact with the ratchet, a rack bar arranged to rotate the pinion whereupon the pin rides off the cam into engagement with the ratchet, finger actuated means including a pitman for operating the rack bar, and means including a stepped regulator movable across the end of the pitman to limit the thrusts thereof and obtain various distances of movement of the pawl.

9. In a writing pad, the combination of a pair of feed rolls, presser rolls coöperating with the feed rolls, yokes supporting the presser rolls and including adjacently located bridge portions, resilient means engaging the bridge portions for urging them together and holding the presser rolls in con-

tact with the feed rolls, a shaft between the bridge portions, and means including cams carried by the shaft, adapted to separate the bridge portions to release the presser rolls from the feed rolls upon partly turning the shaft.

10. A writing pad, comprising a frame, holding means for a paper sheet running over the frame including endless belts and feed rolls, actuating gears included in said holding means, gear cases on one side of the frame covering said gears, and false gear cases on the other side of the frame in duplication of said gear cases, forming legs for the support of the writing pad when placed on a table.

11. A writing pad, consisting of a frame, feed rolls, endless paper holding belts, means for actuating the feed rolls, to draw a paper sheet applied to the belts in one general direction, and squared stub shafts carried by the feed rolls and projecting at one side to enable a reverse movement of either of the rolls for returning the paper sheet a short distance for the purpose of correction.

GEORGE R. CLARK.
